UNITED STATES PATENT OFFICE.

HERBERT C. SEGELKEN, OF PHOENICIA, NEW YORK.

OIL CAN.

Application filed February 23, 1926. Serial No. 90,057.

This invention relates to oil cans, and has for its primary object to provide means whereby a predetermined amount of the oil within the can such as one quart, half gallon, or the like may be withdrawn therefrom, thus overcoming the requirement of providing cans of one, two, three, or four quart measurement.

An additional object is to provide such a construction of can wherein the means for facilitating the discharge of the desired amount may be operated by a thumb lever adjacent the carrying handle of the can and wherein said means will be retained at the desired position.

With the foregoing and other objects in view as the nature of the invention will be better understood, the same comprises the novel form, combination and arrangement of parts hereinafter more fully described, shown in the accompanying drawing and claimed.

In the drawing wherein like reference characters indicate corresponding parts throughout the several views:

Figure 1 is a detail vertical section of my improved can, and

Figure 2 is a top plan view thereof,

Figure 3 is a cross sectional view taken 30 through the telescopically connected pipes.

Now having particular reference to the drawing, my novel can constitutes the provision of a tapered receptacle 5, circular in cross section having a bottom wall 6 in spaced relation to the lower end thereof and a top wall 7 provided with a hinged section 8 in order to permit access to the interior thereof. In the present instance, the container is of such size as to contain one gallon 35 of oil and is provided with a suitable carrying handle 9.

Extending vertically through the can is a stationary pipe 10, the lower end of which is provided with an elbow 11 that extends 45 at right angles through the pipe and projects through an opening in the front side of the can as clearly shown in Figure 1. Joined to the projecting end of this elbow through reason of a flexible pipe section 12 is a discharge nozzle 13 that may be secured to the can through reason of a bracket 14 when the same is not in use.

At predetermined spaced points, and in vertical alignment, said pipe 10 is provided 50 with relatively elongated narrow openings, preferably four in number and designated

15, the spaces between said openings being substantially equivalent to the area of the can that would within said area hold one quart of the fluid therein.

Arranged for rotation within the stationary pipe is a pipe 16, the upper end of which projects through the upper end of the stationary pipe and is internally screw threaded for receiving a plug 17 formed 60 with a vent opening 18. Said rotating pipe 16 is also provided with similarly shaped openings 19 in equivalent spaced relation as said openings 15 in the stationary pipe 10, these openings however being arranged in 65 staggered relation in order that when said pipe 16 is turned in one direction the uppermost opening will first be brought into registration with the uppermost opening in the pipe 10 while a further movement of the 70 pipe will bring the next opening 19 into registration with the next opening 15 of the stationary pipe 10, and so on until the last openings are brought into registration, for 75 thus permitting one quart, two quarts, three quarts, or the entire gallon of the fluid to be dispensed from the can.

Arranged upon the upper projecting end of the movable pipe 16 is a collar 20 provided with a laterally extending arm 21 80 that projects beyond the edge of the can top and is bent upwardly at this end to provide a thumb piece 22. Graduation marks 23 are provided upon the lid of the can as clearly shown in Figure 2, while directly 85 adjacent these graduation marks said lid is provided with upwardly extending beveled lugs 24 over which the arm must ride during its movement to cause a turning of the pipe 16, the graduations 23 indicating the point 90 at which the pipe 16 has been set to facilitate the discharging the proper amount of fuel. The lugs will prevent the reverse rotation of the arms and thus prevent the oil being discharged through the lowermost 100 opening unless the arm has been set to permit of the discharge of the entire contents of the fluid, said arm, graduations, and lugs also combining to indicate to the vendor the amount of fluid that is remaining in the can. 105

It will thus be seen that I have provided a highly novel, simple, and efficient form of oil can that is well adapted for all the purposes heretofore designated and even though I have herein shown and described the most 110 preferred embodiment of the invention with which I am at this time familiar, it is never-

theless to be understood that minor changes may be made therein without affecting the spirit and scope of the appended claim.

Having thus described the invention, what I claim as new and desire to secure by Letters Patent is:—

In an oil can, a receptacle provided adjacent its bottom with a partition and having a top including a hinged cover, said top being provided on its exterior with graduations, stop lugs connected to said top and cooperable with graduations, a stationary tube located in said receptacle and connected with said top and partition respectively, said tube being provided with a row of vertically spaced and aligned openings, a revolu-

ble pipe fitted into said tube and forming a valve, said pipe being provided with a series of spirally disposed openings adapted to be successively and collectively registered 20 with the first named openings, an operating member connected with the upper end of the revoluble pipe and having its outer end co-operable with said lugs, and a substantially right-angular elbow connected to the lower 25 end of said tube adjacent said partition and having its opposite ends extending through the wall of the receptacle below said partition.

In testimony whereof I affix my signature.

HERBERT C. SEGELKEN.
